WHEEL

Dale Whitney, Portland, Oreg., assignor to Whitney Industries, Inc., Portland, Oreg., a corporation of Oregon

Filed June 27, 1968, Ser. No. 12,527

Term of patent 14 years

Int. Cl. D12—14

U.S. Cl. D14—30

FIG. 1

FIG. 4

FIG. 2

FIG. 3

FIG. 1 is a front elevational view of a wheel, showing my new design;

FIG. 2 is a front view of the wheel of FIG. 1, on a reduced scale;

FIG. 3 is a rear view of the wheel of FIG. 1 on the same scale as FIG. 2; and

FIG. 4 is a vertical section taken along lines 4—4 of FIG. 2 on a slightly larger scale than employed in FIG. 2.

The dominant feature of my invention resides in the portion shown in full lines, and the characteristic features thereof reside in the appearance of the front face of the wheel and particularly in the annular concave surface containing bolt head recesses, wherein the wheel spokes extend outwardly from said surface, and wherein said surface has a satiny, machined-like finish.

I claim:

The ornamental design for a wheel, as shown and described.
